UNITED STATES PATENT OFFICE

2,077,679

WATER LEVEL CONTROL FOR BOILERS

George Ernst, Newark, N. J.

Application January 15, 1934, Serial No. 706,778

9 Claims. (Cl. 200—53)

This invention relates to liquid level controls and indicators, and has particular reference to devices intended for high pressure steam boilers.

One object of the invention is to provide a device of this character having control elements such as electrodes mounted in an improved manner in connection with the water column of a boiler but externally thereof.

Another object of the invention is the provision of a device of the nature set forth having a control element or electrode and a valve having improved coaction therewith, whereby removal of the electrode will result in closing of the valve.

Another object of the invention is to provide a device as set forth having improved means whereby the electrodes may be cleaned by a flow therealong.

Another object of the invention is to provide an improved electrode mounting, and an improved combined packing and insulating arrangement.

Essentially the invention aims to avoid the necessity of using gage glasses, which are subject to numerous drawbacks, or floats which require movable mechanism, and to provide a simple, stationary, rugged, entirely safe and reliable device, which can also control the liquid level in any container or boiler.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

40 In the drawing:

Figure 1 is a view in front elevation showing a device embodying the invention.

Fig. 2 is a fragmentary enlarged sectional view taken on the broken line 2—2 of Fig. 1.

45 Fig. 3 is a sectional view of an electrode and mounting therefor.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, there-

fore, is submitted merely as showing the preferred exemplification of the invention.

Referring in detail to the drawing, 10 denotes a device embodying the invention. The same may include a liquid container or high pressure boiler 11 having a water column 12 which may consist of a section of ordinary pipe having vertically spaced tubes 13 secured or welded thereto and flanged at 14 to the boiler. The pipe 12 may be closed as by upper and lower caps 15. In this inexpensive water column, the liquid level is free and is the same as in the boiler.

Connected to the water column 12 at vertically spaced points are a plurality of devices 16 and 17 which may be exact duplicates of each other. Each device may have a one piece valve casing 18 of generally cylindrical form and having a tubular extension 19 connected by a union fitting 20 with the water column. Said valve casing 18 may also have an integral or union connected casing extension 21 embodying a try cock or blow off valve of any suitable type, operative by a cross bar 22 on the stem 23 to control a fluid discharge through the port 24.

Within the valve casing 18 is a central cylindrical chamber 25 communicating with a passage 26 in the tubular extension 19 said passage having preferably a constriction as at 27, which may also afford a valve seat 28 for a ball valve 29. The latter is movable along the passage 26, is retained therein by a cross pin 30, and is adapted to close the passage by engaging the seat 28 under the pressure of fluid from the boiler. Also communicating with the chamber 25 is a connection at 31 leading to the try cock 21.

Interconnecting the devices 16, 17 or specifically the valve casings 18 is an indicating or liquid level control means 53 which may include tubular means having movable or swing joint connection as at 54 with the valve casings at 40 right angles to the axes of connection thereof with the water column, whereby upon turning the valve casings, the means 53 may be raised or lowered as a unit to set the same at the time when the invention is being installed.

The swing connections 54 are duplicates of each other and each may include a series of three elbow fittings 55, 56, 57. Thus the elbow 55 is connected to the valve casing 18 in opposite relation to the try cock 21. The elbow 56 is connected to the elbow 55 for a slight swivel motion. Interconnecting the elbows 56 and 57 is a vertical nipple 58, and the elbow 57 having a slight swiveling motion with the means 53 to which it is connected. Hence in addition to the adjust-

ment above mentioned, a second adjustment is possible, in that the means 53 may be set at an angle to the vertical for a desired purpose, as will be clear hereinafter, and both adjustments may be practised at the same time. For example, if the device 53 includes a pair of vertically spaced indicators, these may be vertically set relatively to each other.

The control means 53 may include one or 10 more vertically spaced control devices 59, 60 which may be duplicates of each other, and are disposed above and below the normal liquid level 5 in the boiler. These control devices may be housed in a one piece casing 61a, which may have 15 duplicate sections 61 for the different devices. Each section 61 may have a chamber 62 having a constricted passage 63 connected to the elbow 51 in alined relation.

Interconnecting the chambers 62 of the casing 20 sections 61 is a passage 72, which thus forms an H with said chambers. Communicating with the passage 72 as at 73 is a try cock or blow off valve 74 which may be exactly like those shown 25 at 21, and the casing of which may be an integral part of or union connected with the casing 61a if desired.

In Fig. 3 is shown a device 109 including an 30 electrode and an improved mounting therefor connected to the casings 18 and 61a, as at 16, 17 and 59, 60 to afford the control hereinbefore mentioned. The devices 109 are duplicates of each other. Each device may include a bushing 110 provided with a central bore 111 communicating with a packing chamber 112, having a 35 series of laminated or other packings 113, compressed by a nut 114. Extending centrally through the bore 111, packing 113 and nut 114 is a threaded stem or electrode 115. The latter may be insulated by the packing 113 and by insulator sleeves 116, 117, of which the former is retained by the nut 114 acting on the annular flange 118 of the sleeve, and the latter by annular end flanges 119 bent or spun against adjacent opposite surfaces of the bushing. Between 40 the insulator ring 116 and the electrode 115 is positioned a pliable contact ring 120 retained by an internal annular end flange 121, and uniformly contacting the electrode under the pressure of the insulation 116, caused especially by 45 the conical opening at 114a in the packing nut 114. A suitable conductor 122 may be connected to an ear or lug 123 of the contact ring. The outer end of the electrode may have a head 124, and the inner end portion thereof may be tapered at 125 and may carry an insulator head 126 for actuating the ball valve 29 wherever the same may be provided. If this electrode is used in the casing section 61, the head 126 may be omitted.

60 In operation, the electrode 115 forms its own thread in the packing 113 and may be screwed in and out thereein. The electrode is reliably insulated from all metallic parts, and the connection at 123 is made so that it is not disturbed 65 by rotation of the electrode. The latter may be completely removed and reinserted, due to the tapered end, without loosening the nut 114, and a new thread may be formed. This device will stand up under the highest boiler pressures. The 70 tapered end portion may be readily cleaned in passages 27 and 63, and may adjustably increase the velocity therethrough and even operate as a needle valve therefor.

The electrodes 115 may be suitably operative 75 to actuate alarm or indicating devices 16, 17 pref-

erably so that the devices 16, 17 operate an alarm if the water level becomes too high or too low. Normally, the water level is intermediate of the electrodes of the devices 59, 60, and when the water level rises to the device 59, any suitable 5 means may be caused to shut off the feed water, whereas if the water level drops to the device 60, the feed water may be turned on or increased, the operation in each case being caused by the corresponding electrode. Where valves 29 are 10 provided, the electrodes can be directly removed. The cleaning of the electrodes may be facilitated by the try cocks 21 and 74 which may also serve to indicate the liquid level. Adequate 15 flushing of the electrodes can be obtained by screwing the electrodes inward of the constrictions 27 and 63, and the electrical resistance of the water can be adjusted in the same manner. The swing joints permit the devices to be raised and lowered to maintain a desired water level, 20 and also permit these devices to be moved toward and away from each other to vary the range of control of said devices. The electrodes are wholly externally accessible for easy removal, inspection and repair, without requiring expensive means for mounting, sealing and insulating the same.

It will be appreciated that various changes and modifications may be made in the device as shown in the drawing, and that the same is submitted in an illustrative and not in a limiting sense, the scope of the invention being defined in the following claims.

I claim:

1. In a liquid level control for boilers, a casing, 35 a valve therein automatically movable into closed position, a free ended electrode in the casing separate of the valve and having at an end thereof a portion of electric insulating material, said electrode being movable relative to the casing to cause said portion to open the valve, electrical insulating packing between the electrode and casing, said electrode having threaded engagement with the packing for movement of the electrode.

2. In a water level control for boilers, a casing member having a recess, a passage communicating therewith, an electrode extending through the recess and passage, pliable electrical insulating packing in the recess, said electrode being threaded and having snug fitting screw engagement with said packing so as to be out of contact with the casing member, an insulator sleeve in said passage freely disposed about the electrode, and a gland element for compressing the packing with the 55 electrode extending through the gland element, and insulator means between the electrode and the gland element, and the electrode being threadedly axially adjustable.

3. In a water level control, an electrode, a casing element having a passage for receiving the electrode, said casing element having a recess in communication with said passage, pliable electrical insulating packing in said recess, a gland element for compressing said packing and being insulated from the electrode, the latter having an external thread for screw engagement with the packing and being spaced from the casing element, and said packing being pressed by said gland into liquid tight engagement with the electrode.

4. A liquid level control, a casing element, an electrode having a threaded shank, said element having a recess and a passage alined therewith, said shank extending through said recess and pas- 75

- sage, electrical insulating means including a sleeve, a pliable packing, and a ring, said sleeve freely receiving the electrode and being fitted in said passage, said sleeve having a flange portion 5 secured in the recess, said packing being in the recess and extending around said shank, a gland compressing said packing into liquid tight screw engagement with the electrode shank, the latter being wholly out of contact with the casing element, said gland having a hole for receiving the shank, a conductor member having wiping contact with the shank, and said ring extending around the shank and overlying the conductor to retain the same in position, with said gland bearing 15 on the said ring.
5. In a liquid level control, an electrode having an elongated threaded shank, and means for sealingly mounting the same including a casing element and initially unthreaded pliable electrical insulating packing therein through which said shank extends, and means to compress the packing uniformly about the shank and in engagement with the thread thereof to provide a screw threaded connection between the electrode and the packing for sealing the electrode tight under high pressures and in spaced relation to the casing element.
6. In a liquid level control, an electrode having an elongated threaded shank, and means for sealingly mounting the same including a casing element and initially unthreaded pliable electrical insulating packing therein through which said shank extends, and means to compress the packing uniformly about the shank and in engagement with the thread thereof to provide a screw threaded connection between the electrode and the packing for sealing the electrode tight under high pressures and in spaced relation to the casing element, and said electrode having a tapered 35 end adapted for easy initial insertion into the packing.
7. In a liquid level control, an electrode having an elongated threaded shank, and means for sealingly mounting the same including a casing element and initially unthreaded pliable electrical insulating packing therein through which said
- shank extends, and means to compress the packing uniformly about the shank and in engagement with the thread thereof to provide a screw threaded connection between the electrode and the packing for sealing the electrode tight under high pressures and in spaced relation to the casing element, and said electrode having at an end thereof a portion consisting of electrical insulating material, said end portion being adapted for actuation of a valve element by screw adjustment 10 of the electrode in said packing.
8. In a liquid level control, an electrode having an elongated threaded shank, and means for sealingly mounting the same including a casing element and initially unthreaded pliable electrical insulating packing therein through which said shank extends, and means to compress the packing uniformly about the shank and in engagement with the thread thereof to provide a screw threaded connection between the electrode and the packing for sealing the electrode tight under high pressures and in spaced relation to the casing element, and a valve separate of and movable by the electrode on screw actuation of the latter along said packing.
9. In a liquid level control, an electrode having an elongated threaded shank, and means for sealingly mounting the same including a casing element and initially unthreaded pliable electrical insulating packing therein through which said shank extends, and means to compress the packing uniformly about the shank and in engagement with the thread thereof to provide a screw threaded connection between the electrode and the packing for sealing the electrode tight under high pressures and in spaced relation to the casing element, and said casing element including a fluid passage having a constricted orifice portion into an entrance of which an end of the electrode adjustably axially extends to a degree determined by screw actuation of the electrode with respect to the packing, whereby the said end of the electrode can be cleaned by said fluid.
